UNITED STATES PATENT OFFICE.

MILES E. BERRYE, OF NEW YORK, JAMES A. KANE, OF BROOKLYN, AND JOHN E. STENGARD, OF NEW YORK, N. Y.

CANDY PULLING OR AERATING MACHINE.

SPECIFICATION forming part of Letters Patent No. 728,075, dated May 12, 1903.

Application filed December 1, 1902. Serial No. 133,463. (No model.)

To all whom it may concern:

Be it known that we, MILES E. BERRYE, a citizen of the United States, residing at New York, in the county of New York, JAMES A. 5 KANE, a citizen of the United States, residing at Brooklyn, in the county of Kings, and JOHN E. STENGARD, a subject of the King of Sweden and Norway, residing at New York, in the county of New York, State of New York, have 10 invented new and useful Improvements in Candy Pulling or Aerating Machines, of which the following is a specification.

By means of this invention the operation of pulling or aerating candy can be effectively 15 accomplished.

This invention resides in suitable mechanism adapted for carrying out the above object, the novel features of the invention being set forth in the following specification and 20 claims and illustrated in the annexed drawings, in which—

Figure 1 is a side elevation of a device embodying this invention sectioned along xx , Fig. 2. Fig. 2 is a plan view of the device 25 sectioned along yy , Fig. 1.

The gear-wheel a is provided with the arm or shaft b , carrying the central spools $c c$, which can turn freely on the said shaft. The arms $e e$ are fastened to the shaft b and carry 30 the rotating arms m , with spools $f f$ swinging about the central spool c and the shaft b . The gear-wheel d is provided with an eccentric-pin g , actuating the link h and giving the arm i oscillating motion. This arm i has

35 attached to one end of it the arm n , with spools $j j$, which can turn freely around their axial supports or arm n . The gears a and d are rotated by the driving-gear k , rotating the transmission-gear l . The gear-wheel a 40 rotates twice while gear d rotates once, so that the spools f of arms $e e$ will pass between arms b and n or inside of the spools $j j$ by one revolution of gear a and then outside of the said spools or about both arms b and n 45 by the next revolution. Each spool is rotative on its spindle or arm, and the spools are shown in pairs to make the machine double-acting; but a single-acting machine with spools only on one side of the machine is included in the invention.

It may be noted that the various arms b ,

m , and n would pull or work candy without the spools; but spools applied as shown have been found to give satisfaction. Such rotary spools tend to prevent the candy from twisting and tend to preserve the running grain or the parallel air-cells of the candy.

55 The arm b may for convenience of description be called a "central" arm, said arm not changing its place, although in the construction shown said arm rotates about its axis.

The arm m rotates on the plan of a crank-pin or has a planetary motion about the center or arm b , said arm m being shown keyed or secured by its arm or web portion e to the 60 central arm or rotating shaft b . The oscillating arm n has its supporting-arm i suitably mounted or pivoted at o .

The machine can be made of suitable material. Metal has been found satisfactory.

70 What we claim as new, and desire to secure by Letters Patent, is—

1. A candy-pulling machine comprising a central arm, a rotating arm and an oscillating arm.

75 2. A candy-pulling machine comprising a central arm, a rotating arm made to rotate or swing about the central arm, and an oscillating arm made to move toward and from the central arm.

80 3. A candy-pulling machine comprising a central arm, an oscillating arm, and a rotating arm made to move about both the central and oscillating arms and to move also between said two arms.

85 4. A candy-pulling machine comprising a central, a rotating and an oscillating arm, and spools for the arms.

90 5. A candy-pulling machine comprising a rotating arm, an arm for carrying said rotating arm, and an oscillating arm made to move toward and from said rotating arm.

95 6. A candy-pulling machine comprising a gear, an arm rotated by the gear, a rotating arm carried by said first-mentioned arm, a second gear made of different size from the first-named gear, and an arm oscillated by the second gear.

100 7. A train of gears meshing with one another and two of said gears being of different sizes, a rotating arm, an arm for carrying said rotating arm, said last-mentioned

arm being operated by one of said gears, an eccentric-pin on the other of said gears, a link connected to said pin, and an arm oscillated by said link.

- 5 8. A candy-pulling machine comprising arms, mechanism for respectively rotating one arm and for oscillating another of the arms, and spools rotatively mounted on the arms.
- 10 9. A candy-pulling machine comprising arms and mechanism for actuating said arms,

one of the arms being made to oscillate and the other arm being made to rotate.

In testimony whereof we have hereunto set our hands in the presence of two subscribing ¹⁵ witnesses.

MILES E. BERRYE.
JAMES A. KANE.
JOHN E. STENGARD.
